UNITED STATES PATENT OFFICE.

HERBERT SPENCER POWELL, OF CLINTON, NEW YORK, ASSIGNOR TO
POWELL MUFFLER & TIMER COMPANY, OF UTICA, NEW YORK.

MUFFLER.

No. 833,241.

Specification of Letters Patent.

Patented Oct. 16, 1906.

Application filed January 8, 1906. Serial No. 295,001.

To all whom it may concern:

Be it known that I, HERBERT SPENCER POWELL, of Clinton, in the county of Oneida and State of New York, have invented certain new and useful Improvements in Mufflers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The object of my invention is to provide a strong and efficient muffler for explosive-engines and one which is economically manufactured, is well adapted to withstand the detrimental effects of expansion and contraction, and is free from resonant troubles.

Figure 1 of the drawings shows a side elevation of a muffler of my improved construction. Fig. 2 shows a longitudinal section of the same. Fig. 3 is a partial end view as seen from the left-hand end of Fig. 1. Fig. 4 is a partial view of one of the sections from which the muffler is constructed.

Referring to the reference-letters in a more particular description, *a* indicates one of the several similar sections from which the muffler is constructed, said sections being drawn metal cups of a truncated-cone form, having the bottom *b* of each section in the smaller or reduced end and the open end of a diameter to receive the reduced end of the next adjacent section, while the bottoms of the sections are spaced apart, thereby affording the chambers *c*, *c*, &c. The several sections *b* are provided with numerous holes or openings, as *d*, through the bottoms *b*, and these openings are preferably arranged in a circle adjacent to the outer shell of the section. In the first section there is provided a head *e*, having an inlet-opening *f*, preferably screw-threaded, as shown, to receive the end of a pipe. The several sections are held together by a pair of rods *g*, *g*, extending longitudinally through the length of the muffler, through the head *e*, and the bottom *b* of the final sec-

tion. The openings in the final section *b* are indicated by *h* and are preferably of less diameter than the openings in the heads or bottoms of the several main sections.

By tension on the rods *g* the base of each section is firmly wedged into the open end of the next adjacent section and the construction is very stiff and substantial. The discharge from the gas or explosive engine is received through the inlet-opening *f* and distributed and discharged into the several successive chambers *c* until it is finally allowed to escape at the openings *h*. The discharge from gas and explosive engines is usually quite hot and has a very detrimental effect upon the muffler. The fact that the sections of this muffler can be readily constructed from drawn steel and that the bottom or closed end of each section stands practically in the mouth or open end of the section with which it engages, the detrimental effect of expansion and contraction is reduced to the minimum and resonant troubles due to vibration of sections or parts is reduced to a minimum or entirely eliminated.

It is evident that some changes and variations in *g* and from the construction herein shown and described may be made without departing from the spirit of my invention.

What I claim as new, and desire to secure by Letters Patent, is—

A muffler for explosive-engines consisting of a series of similar cup-shaped tapering sections partially nested to provide a series of undivided and unobstructed expansion-chambers *c*, *c*, the bottom of each section being perforated with numerous holes for the diffusion and passage of gases directly from one chamber to the other, and a head with an inlet-opening provided in the first section, substantially as set forth.

In witness whereof I have affixed my signature, in presence of two witnesses, this 30th day of December, 1905.

HERBERT SPENCER POWELL.
